(57) CLAIM

The ornamental design for a cosmetic brush, as shown and described.

DESCRIPTION

FIG. 1 is a front elevational view of a cosmetic brush showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a perspective view thereof;

FIG. 8 is a front view of the handle with the hair removed;

FIG. 9 is a perspective view of handle with hair removed; and,

FIG. 10 is a top view of the handle with the hair removed. The broken lines in the drawings depict portions of the cosmetic brush that form no part of the claimed design.
